DESIGN FOR A CREAM JAR

Frank McLaughlin, Chicago, Ill., assignor to Carr-Lowrey Glass Co., Baltimore, Md.

Application September 19, 1936, Serial No. 64,928

Term of patent 14 years

To all whom it may concern:

Be it known that I, Frank McLaughlin, a citizen of the United States, residing at Chicago, in the county of Cook and State of Illinois, have invented a new, original, and ornamental Design for a Cream Jar, of which the following is a specification, reference being had to the accompanying drawing, forming part thereof.

I claim:—

The ornamental design for a cream jar, as shown,

FRANK McLAUGHLIN.
